RETAINING RING FOR PERCOLATOR TOPS

Nick Sciurba, Chicago, Ill.

Application July 22, 1946, Serial No. 685,561

4 Claims. (Cl. 220—82.5)

1

This invention relates to improvements in retaining means for the glass domes of percolator tops, and refers specifically to a retaining means which permits quick and convenient mounting or removal of the dome from the percolator top or cover and yet when in retaining position holds the dome positively upon the cover.

One of the features of the invention resides in the provision of a retaining means which can be manufactured and sold inexpensively and which can be simply and conveniently employed with the usual percolator dome.

Other objects and advantages of my invention will be apparent from the accompanying drawing and following detailed description.

Fig. 1 is a sectional elevational view of a percolator top having the dome portion thereof secured by the retaining means comprising my invention.

Fig. 2 is a plan sectional view taken on line 2—2 of Fig. 1.

Fig. 3 is a bottom plan view of the retaining ring comprising my invention.

Fig. 4 is a side elevational view, parts being broken away and parts being shown in section, of a modified form of retaining ring.

Fig. 5 is a bottom plan view of the device illustrated in Fig. 4.

Fig. 6 is a detailed sectional view taken on line 6—6 of Fig. 5.

Referring in detail to the drawing, 1 indicates the usual percolator top or cover. The cover 1 is provided with a central opening defined by an inwardly or downwardly turned flange 2, the flanged opening being adapted to function as a seat for a dome 3 of the usual construction. The dome 3 is constructed of glass and is of hollow structure and functions as a knob or handle for the cover 1 and also serves to distribute the liquid, which is projected upwardly in the form of a jet into contact with the interior of the dome, over the coffee grounds which are positioned immediately beneath the cover 1 in the usual percolator. The dome 3, being of transparent material, also permits the operator to observe the percolating action which takes place within the percolator.

The dome 3 is provided with an annular bead 4 of substantially semicircular cross-section. Beneath the bead the dome terminates in the form of a cylinder 5, which portion normally projects a relatively short distance into the interior of the cover 1.

As a feature of my invention I employ an annular ring 6 having an internal diameter sub-

2

stantially equal to the external diameter of the annular bead 4. The upper edge of the ring 6 is flanged inwardly as indicated at 7 in Figs. 1 and 3 whereby said ring can be brought to embracing engagement with respect to the bead 4. A plurality of angularly spaced tongues 8 are formed integral with the ring 6 and project from the lower edge of said ring. The upper portions of the tongues 8 are crimped inwardly, as shown best at 9 in Fig. 1, so that said upper portions embrace the lower sectional contour of the bead 4.

It is to be understood, of course, that as many tongues as desirable may be employed. It is preferable that the tongues be spaced at substantially equal angles from each other as in the case illustrated wherein the tongues are spaced at 120° from each other. The ring 6 may be constructed of a metallic material and the tongues 8 may be formed integral therewith. However, if desired, the ring 6 may be constructed of a plastic material in which metallic tongues similar to the tongues 8 may be imbedded.

With the ring 6 mounted upon the bead 4 and the upper portions of the tongues 8 crimped inwardly to engage the lower edge of the bead 4, the tongues 8 will be disposed substantially parallel to the surface of the cylindrical portion 5. The dome 3 may then be positioned upon cover 1 with the cylindrical portion 5 inserted within the flanged opening of the cover. The tongues 8 will then be positioned between the surface of the cylindrical portion 5 and the annular flange 2. The tongues 8 may then be bent radially so as to engage the lower edge of the flange 2.

When it is desired to remove the dome 3 from the cover 1 for purposes of cleaning or replacement, it is merely necessary to straighten the tongues 8 and remove the dome 3.

Referring particularly to Figs. 4, 5 and 6, a modification of my invention is illustrated. In this form of my invention I contemplate the use of an annular ring 10 which is of substantially semicircular cross-section conforming substantially with the outer contour of bead 4 of the usual percolator dome. The ring 10 is split at one portion of its periphery as indicated at 11 in Figs. 4 and 5 whereby the ring may be conveniently positioned in engagement with the bead 4. The ring 10 is provided with a plurality of depending tongues 12, 13 and 14. The tongues 12 and 13 are spaced at a predetermined angular distance from each other approximately the same angular distance as each tongue is spaced from the tongue 14. One tongue 14 is positioned im-

mediately adjacent each end of the ring at the space 11.

With the ring 10 mounted upon the bead 4 the tongues 12, 13 and 14 are disposed substantially parallel of the cylindrical portion 5 of the dome 3. The dome may then be positioned upon the cover 1 and each of the tongues may be bent radially outwardly to lock the ring, and hence the dome, upon the cover 1. It will be noted, however, that when the tongues are inserted with the dome 3 within the opening in the cover 1, the ring 10 is drawn into snug engagement with the bead 4. Therefore, the tongues 12, 13 and 14 form a dual purpose of securing the ring 10 upon the bead 4 and simultaneously, when said tongues are bent, securing the ring and the dome 3 upon the cover 1.

It is obvious that other modifications of my invention may be suggested to those skilled in the art, and hence I do not wish to be limited except as necessitated by the prior art.

I claim as my invention:

1. A retaining device for securing the usual percolator dome of the type having an annular marginal bead adjacent its lower end to a percolator cover having a circular central opening for the reception of said dome, which comprises an annular ring one side of which is adapted to embrace one side of substantially the entire periphery of said bead, tongues of bendable material carried by the opposite side of said ring and extending transversely from said side of the ring, said tongues being adapted to be positioned in said central opening when the dome is mounted upon said cover and bent radially outwardly into locking engagement with the defining edge of said central opening.

2. A retaining device for securing the usual percolator dome of the type having an annular marginal bead adjacent its lower end to a percolator cover having a circular central opening for the reception of said dome, which comprises an annular ring constructed of bendable material one side of which is adapted to embrace one side of said bead, circumferentially spaced tongues formed integral with said ring at the opposite side of said ring and extending trans-

versely from said side of said ring, said tongues being adapted to be positioned in said central opening when the dome is mounted upon the cover and bent radially outwardly into locking engagement with the defining edge of said central opening.

3. A retaining device for securing the usual percolator dome of the type having an annular marginal bead adjacent its lower end to a percolator cover having a circular central opening for the reception of said dome, which comprises a split annular ring of substantially semicircular cross-section adapted to embrace said bead, said ring being constructed of bendable material, tongues formed integral with said ring and extending in parallel relation from one side thereof, said tongues being positionable in said central opening when the dome is mounted upon the cover and bendable radially outwardly into locking engagement with the defining edge of said central opening.

4. A retaining device for securing the usual percolator dome of the type having an annular marginal bead adjacent its lower end to a percolator cover having a circular central opening for the reception of said dome, which comprises a split annular ring of substantially semicircular cross-section adapted to embrace said bead, said ring being constructed of bendable material, angularly spaced tongues formed integral with said ring and extending in parallel relation from one side thereof, said tongues being positionable in said central opening when the dome is mounted upon the cover and bendable radially outwardly into locking engagement with the defining edge of said central opening.
